ARTICLE FEEDING AND PRINTING
APPARATUS

Frank W. Sawtelle, Keene, N.H., assignor to Markem
Machine Company, Keene, N.H., a corporation of New
Hampshire

Filed Mar. 8, 1961, Ser. No. 94,246
16 Claims. (Cl. 101—37)

This invention relates generally to printing apparatus and more particularly to improved apparatus for printing identifying indicia on capsules, tablets and similar small articles.

A wide variety of small articles are now being manufactured, including pharmaceutical materials, such as gelatin capsules and tablets, and miniature electrical components, on which it is frequently desired to place an identifying or informational legend. A usual requirement in this field is that the identifying legend or other indicia be placed in sharply delineated form in a precise position on the article. Also it is not infrequently desired to mark opposite surfaces of the articles with the same or different legends. In all cases the printing apparatus must mark the article in accordance with the standards set by the user, rapidly, in an economical manner and without damage to the article being marked. Prior attempts to provide apparatus capable of feeding the articles rapidly, in proper alignment and in coordination with the printing mechanism so that the legend is precisely applied in the desired location, have generally involved the use of several complex mechanisms which were often found to be unreliable in operation and to demand a considerable amount of maintenance.

Accordingly, it is an object of this invention to provide a simple and improved printing apparatus for placing indicia on small articles such as capsules or tablets.

Another object of the invention is to provide an improved article printing mechanism and associated feeding apparatus which are driven in coordinated manner by a single drive means.

Still another object of the invention is to provide an improved feeding mechanism for use with the printing apparatus which automatically positions the articles for printing.

A further object of the invention is to provide an improved article feeding apparatus adapted to be used in conjunction with printing apparatus which enables indicia to be simultaneously placed on opposite surfaces of the article.

A related object of the invention is to provide an improved printing apparatus capable of applying indicia to opposite sides of small articles in a simultaneous manner.

In accordance with the preferred embodiment of the invention there is provided a feeding apparatus comprising a feeding disc which has a multiplicity of notches or outwardly opening pockets evenly spaced about its periphery. These notches or pockets have a shape which conforms substantially to the shape of the article to be printed. A stationary guide structure surrounding the disc has an upstanding cylindrical wall positioned closely adjacent the periphery of the disc which tends to retain the article in the pocket and a lower inwardly extending portion positioned beneath the disc which functions as a floor under the periphery of the disc to support the articles when they are positioned in the pockets. The combination of disc and cylindrical guide structure is preferably tiltable through a range of inclinations and is arranged to provide a large hopper into which a multiplicity of the articles to be imprinted may be deposited. The disc, positioned at an inclined angle, is rotated so that articles in the pockets are carried upwardly past the highest point

2

of the hopper and through a printing mechanism that is positioned in the path of the pockets in the disc periphery. The angle of inclination of the disc may be varied in accordance with the nature of the articles being fed by the apparatus and the disc is mounted so that it may be easily removed and another disc having different pocket configurations may be substituted. The apparatus is designed so that it may be easily adapted to feed different types and configurations of articles.

10 The printing apparatus utilized in the preferred embodiment of the invention includes two sets of rotary printing mechanisms which have offset rolls disposed on opposite sides of the path of the articles as fed by the disc. Each offset roll picks up a configuration of ink impression from engraved rolls and transfers that ink configuration to the article as it is moved past it by the feeding disc. The engraved rolls are adjustably mounted on gear driven shafts and they may be easily and accurately rotated so that proper registration of the two indicia printed by them on the article as positioned and fed by the feeding disc is achieved. The two printing units and the feeding disc are directly driven by a common power source so that the printing operation is accomplished in a coordinated and inter-related manner. The 15 apparatus of the invention is a comparatively simple mechanism which permits printing of the articles at rates of up to several thousand articles per minute and is capable of easy adjustment to receive a wide variety of types and sizes of articles to be printed. It is a reliable, 20 versatile and compact apparatus which is capable of applying indicia on opposite sides of articles simultaneously at high rates of production and which requires comparatively little maintenance.

Additional objects, features and advantages of the invention will be seen as the following description of a preferred embodiment thereof progresses in conjunction with the drawings, in which:

FIG. 1 is a side elevational view of the printing apparatus according to a preferred embodiment of the invention showing details of the feed hopper structure, the printing mechanism, and the drive apparatus for the feeding apparatus and the printing mechanism;

FIG. 2 is an elevational view of the opposite side of the apparatus showing additional details thereof;

45 FIG. 3 is a rear elevational view of the apparatus showing details of the drive and of certain of the adjustment mechanisms employed in this embodiment;

FIG. 4 is a top view of the apparatus taken along the plane of the feeding disc;

50 FIG. 5 is an enlarged view of a peripheral portion of one type of feeding disc of the type utilized for the feeding of capsules;

FIG. 6 is an enlarged view of a small portion of a second form of feeding disc of the type suitable for feeding 55 flat cylindrical tablets;

FIG. 7 is a sectional view taken along the line 7—7 of FIG. 5 showing the feeding disc, the fixed hopper structure and details of the apparatus provided in the preferred embodiment of the invention for removing misaligned or 60 extra articles being carried by the feeding disc;

FIG. 8 is a sectional view of a portion of the feeding disc and the apparatus for preventing feeding of articles even though the drive apparatus is operative;

65 FIG. 9 is a view of a portion of the feeding disc and the printing apparatus utilized in the preferred embodiment of the invention;

FIG. 10 is a sectional view along the line 10—10 of FIG. 9 illustrating details of the printing apparatus drive mechanism; and

70 FIG. 11 is a sectional view taken along the line 11—11 of FIG. 9 of the ink reservoir reciprocating mechanism for the printing apparatus.

As shown in FIGS. 1-4 the apparatus of the preferred embodiment of the invention is mounted on a base 10 and includes a drive motor 12 which drives the article feeding apparatus and the printing mechanism through a set of sheaves 14, 16, drive belt 18 and a speed reducer mechanism 20. The output shaft of the speed reducer mechanism drives chain belts 22 and 24 which rotate a cross shaft 26 (best seen in FIG. 4) which drives both a printing mechanism generally indicated at 28 and a feeding apparatus generally indicated at 30. The printing mechanism and feeding apparatus are mounted as a unit for pivoting movement about the shafts 32 supported from studs 34 upstanding from base 10. A sprocket driven by chain 22 and a sprocket which drives chain 24 are secured to a shaft positioned on the axis of stub shafts 32. The support for the feeding and printing unit includes a base member 36 which is secured at one side to the upstanding studs 34 and may be angularly adjusted about the stub shafts 32 by means of the hand crank 40 (FIG. 3) which acts through a set of gears 42, 44 to rotate the link 46 on the threaded shafts 48. The shaft 48 is pivotally secured to the fixed base 10 by connection 50 and its upper portion 49 passes through the adjustable base 36. Thus the angle of inclination of both the feeding apparatus and the article printing apparatus may be easily varied as a unit as desired in accordance with the nature of the articles being printed.

The feeding apparatus 30 includes a cylindrical wall structure 52 supported by upstanding bracket members 54 and a feeding disc 56 which is clamped down on flange 57 secured to the end of drive shaft 58. The disc 56 is held on the flange 57 by means of a flat plate 59 (FIG. 8) and nut 60 which cooperates with a threaded extension 61 of flange 57. Three leveling screws 62 provide an adjustment which insures that the feed disc 56 may rotate in a plane without wobble, and a locating pin 63 engages the disc to assist in positioning and drive of the disc. The disc drive shaft 58 is mounted within housing 64 and is driven by a gear 65 (which meshes with a co-operating gear 66 that is mounted on the shaft 26 driven by the chain belt 24).

The printing apparatus 28 is also mounted on the tilting plate structure 36 and is tilted with the feeding apparatus 30 by the operation of the hand wheel 40. The printing structure is supported on a set of outwardly extending ways which permit the printing unit to be moved inwardly and outwardly by rotation of the hand wheel 67 (FIG. 3) which rotates a threaded shaft 68 (secured to the printing unit) that cooperates with a threaded channel 69 on the block 70 mounted on support plate 36. The printing unit drive includes a square shaft 71 which normally engages a co-operating slot in one member of universal joint 72 (driven by shaft 26). Driven by the square shaft 71 is a gear train which commences with gear 73. As is indicated in FIG. 4 (by dotted lines) the printing unit may be moved laterally outward along the ways until shaft 68 no longer engages channel 69 at which time the printing unit may be slid entirely off the ways. A vernier adjustment associated with shaft 68 enables fine lateral positioning of the printing unit.

Thus both the printing apparatus 28 and the feeding structure 30 are mounted as a single unit and are driven in coordinated manner by the one drive motor 14. Drive speed adjustment is provided by the hand wheel 74 which cooperates with threaded shaft 76 and block 78 on which the motor is mounted to move the motor 12 laterally with corresponding adjustment in the effective diameters of sheaves 14 and/or 16. Positive drives (gears or chains) insure the maintenance of the desired relation between the feed disc 56 and the printing mechanism 28.

A top view of the apparatus taken of the plane of the disc 56 is shown in FIG. 4. The disc is manufactured from hard rubber or other similar material having a degree of resilience so as to minimize damage to the articles being fed. The disc has in its periphery a multi-

plicity of evenly spaced notches or outwardly opening pockets 32. Two examples of types of discs that may be utilized are shown in FIGS. 5 and 6. In FIG. 5 the pockets 32 are elongated and adapted to receive capsules 34. In FIG. 6 they are shown as semi-cylindrical pockets for receiving tablets 36. It will be noted that the notch conforms closely with the shape of the article to be fed by the disc. Other pocket configurations may of course be employed so that the various other types of small articles may be received and fed by the apparatus of the invention.

The structure surrounding the disc includes an upstanding cylindrical wall portion 90 and inwardly extending floor portion 92. Connecting these two surface portions as shown in FIG. 7 is an inclined surface 94 which is preferably disposed at an angle of about 45°. The surfaces adjacent the disc are chromium plated and have a high polish so that friction, and possible damage to the articles being fed, is minimized. The inwardly extending floor portion 92 supports the articles when they are positioned in the notches 32 and they slide on this floor portion as they are advanced by the disc to the printing station. Depending on the speed of rotation of the disc the articles carried in the notches are exposed to a degree of centrifugal force which tends to urge them outwardly toward the cylindrical wall portion 90 such that they tend to ride up the inclined surface portion 94. This reaction however is opposed by gravity which aids in maintaining the articles in the notches for proper feeding. A hopper wall extension 95, clamped to the wall portion 90, increases the effective size of the hopper so that more articles may be placed therein at one time for feeding.

The hopper structure in normal operation is tilted at an angle of 15-45°, preferably between 22° to 36° with respect to the horizontal, with the lowest portion thereof to the left as shown in FIG. 4. The hopper structure is arranged to hold a multiplicity of articles for feeding and the disc is driven in a counterclockwise direction as indicated by the arrow in FIG. 4. Elongated articles are aligned with the pockets under the influence of the disc's rotation and drop into them to be carried upwardly and around the hopper edge to the printing apparatus 28. A scoop structure 96 (FIGS. 2 and 4) is secured to the wall adjacent the end of the hopper extension 95 by clamp means 97. This scoop has a lower edge positioned just above the top of the disc 56 and outwardly of the notches 32 and rises gradually to a height above the disc. Articles which lie to the outside of the disc but are carried thereby (in engagement with an article in a notch for example) hit the scoop and ride upwardly and then are dropped from sufficient height so that they roll across the disc surface and are returned to the common mass of articles. At the upper portion of the hopper there is mounted on the surrounding wall structure 90 two air jet structures 98, 99, each of which has an orifice 100 positioned to direct an air flow inwardly across the surface of the disc as indicated in FIG. 7. These air jet structures are secured by means of a clamp 101 and bolt 102 to the upstanding wall portion 90 of the cylindrical hopper structure 52. As the disc 56 rotates and carries articles past these jets any article that is riding on another article or on the bridge between notches is forced inwardly away from the disc periphery and down to the common mass of articles in the hopper. In this manner it is insured that improperly positioned articles are not carried to the printing unit by the disc.

Another air nozzle 104 is positioned between the two jets 98 and 99 and has an orifice opening upwardly through the floor position 92 (see FIG. 8) and the air flow tends to force all the articles out of the pockets and up against the deflector 105, clamped on the wall 90, which deflects them inwardly for return to the common mass and they are not fed to the printing apparatus by the disc. This air jet 104 is turned on only when no articles are to be fed, for example, to give oppor-

tunity for inking the rolls, adjusting, etc. Each jet or nozzle is connected to a suitable source of air pressure through a conduit 106. It will be noted that an additional safeguard is provided at the downward feeding side of the disc in the form of a barrier plate 108 which is secured to the wall 90 and acts to deflect articles not positioned in the notches from the area of the printing apparatus 28.

In the feeding operation, the articles to be fed are loaded into the hopper and fall into the notches where they are held and advanced in proper aligned position as the disc rotates. They are moved upwardly toward the scoop 96 and the nozzle jets 98, 99 and any articles on the surface of the disc or not properly positioned in a notch tend to be forced inwardly across the surface of the disc. Finally, all articles on the surface of the disc are prevented from moving toward the printing apparatus by the barrier member 108 positioned closely adjacent the surface of disc 56. Thus these several devices insure that only articles properly positioned in the notches 82 are fed to the printing apparatus 28.

The printing apparatus 28 (best shown in FIG. 9) comprises two printing mechanisms each of which includes an offset roll 120, 122, an engraved roll 124, 126 and an ink fountain structure 128, 130 respectively. Each ink fountain is adapted to contain the ink or other printing medium and cooperates with the associated engraved roll to apply ink directly to depressions in the surface of that roll. The excess of ink is removed from the engraved roll by a blade 132 which is oscillated or otherwise reciprocated in conventional manner. An eccentric cam structure 134 drives arm 136 to reciprocate the entire ink fountain structure as generally indicated in FIG. 11. Each engraved roll preferably includes an outside layer of chrome plated on copper and has depressions engraved in its surface in the form of the indicia that are to be printed on the articles. The ink applied from the fountain collects in these depressions with the excess being wiped off by the reciprocated blade 132. The offset roll, which may be manufactured from any of the rubber-like materials conventionally utilized for such rolls, is positioned in contact with the engraved roll. The ink configurations carried by the depressions are transferred to the offset roll and then from the offset roll to the articles in printing operations. The offset rolls are preferably tapered as shown in FIG. 10 leaving a peripheral surface of sufficient width to receive the ink from the depressions in the engraved wheel while providing a greater degree of angular flexibility to accommodate slight differences in speed of the roll and the article contacted so that the ink configuration is not smeared. The sets of rolls are gear driven so that the possibility of relative slippage with consequent smearing of the ink during transfer operations is minimized. The axes of the two printing mechanisms may be adjusted with the top offset roll shaft moving along through the paths indicated by the groove 140 shown in dotted lines to adjust the space between them. An adjusting screw 142 controls the position of the spring loaded offset roll shaft 144.

As indicated in FIG. 10 each printing apparatus is supported on the upstanding wall 146 with each shaft passing through a bushing. Thus the shaft 148 of the offset roll passes through bushing 150 and the shaft 152 of the engraved roll 126 passes through the bushing 154. A gear 156, 158 respectively is mounted on each shaft and is seated on a shaft shoulder. A second gear 160 is mounted on shaft 152 and the gear or gears on each shaft are securely locked thereon by a washer 162 and a nut 164. The tightening of the nut 164 seats the gear on the shoulder portion of the shaft and secures it in the desired relation. A hex head portion 166 on each shaft between the bushing and the associated roll is provided to facilitate the angular adjustment of the

roll. In this way the shaft and its roll easily may be rotated through a few degrees or a fraction thereof relative to the gear train and thus the relative positions of legends applied to each article by the two printing apparatuses may be easily adjusted. Each roll is secured on its shaft by a threaded disc 168 which is tightened down to secure the roll on the shaft by suitable means such as a spanner.

The gear train which drives the printing units is shown in FIG. 1. Both units are driven from the gear 73 which meshes with gear 170. That gear in turn drives with gear 160 which is mounted on the shaft 152 of gravure roll 126. Also mounted on shaft 152, as indicated above, is gear 158 which meshes with and drives gear 156 mounted on the offset roll shaft 148. Gear 156 also drives gear 172 and through that gear the gravure roll gear 174 and the offset roll gear 176 of the other printing apparatus. Mounted on the same shaft as gear 172 is a gear 178 which cooperates with a gear 180 to rotate shaft 182 which in turn, through universal joint 184, drives the shaft 186. Mounted at the end of this shaft 186 is an eccentric cam 134 (as shown in FIG. 10) which reciprocates the ink fountain structure 130. A similar cam associated with shaft 182 reciprocates the ink fountain structure 128. Thus the two printing units are driven through a single gear train with the gearing engineered so that the peripheral speed of the gravure rolls is the same as the peripheral speed of the disc. In other words the ink configurations are transferred from two gravure rolls, moving at equal speeds, via offset rolls to an article that is moved by the feeding disc at the same speed as the offset rolls. The adjustment screw 142 for controlling the position of the top roll and thus the nip between the offset rolls acts to pivot shaft 144 of roll 140 about a center defined by the shaft of the associated gravure roll 124.

As may be seen in FIG. 9 the floor portion 92 of the hopper structure is cut away in the immediate vicinity of the offset rolls so that the articles to be printed are slid by the disc 56 directly from the lip of the floor 92 into the nip between the offset rolls 120 and 122 and are advanced by the disc 128 past those offset rolls. All elements (the periphery of the disc 56, the peripheries of the two offset rolls 120, 122 and the articles) move at the same speed in that area so that accurate, unsmeared ink configurations as carried by the offset rolls are transferred to each article. After printing the article is discharged from the offset rolls and falls freely as indicated in FIG. 9 into a suitable receptacle.

The common drive arrangement coordinates the operation of the printing mechanism and the movement of the articles past them. It will be obvious that the spacing of the engraved indicia on the gravure rolls 124, 126 should equal the spacing between pocket centers on the disc. Proper registration of the indicia printed on opposite sides of the article is thus insured. Adjustments of the positions of the two printed marks relative to one another may be made by freeing a nut 164 on a gravure roll shaft and turning the shaft via the associated hex head portion 166 slightly. In addition it will be noted that the apparatus permits easy changing of both the feeding disc for accommodating other shapes or sizes of articles and the gravure rolls to enable accurate high speed printing of the different types of articles. Other adjustment features include speed changing, hopper angle modification and lateral positioning of the printing unit (including the facility of removing the printing unit from the feeding unit entirely).

Thus it will be seen that the apparatus provides an improved feeding mechanism and printing apparatus particularly adapted for placing indicia on opposite surfaces on small articles. The feeding apparatus is a simple mechanism which is reliable in operation, is capable of easy modification to handle different articles and requires

a minimum amount of maintenance. The printing apparatus enables application of legends to two surfaces of an article substantially simultaneously. It is particularly adapted for association with the feeding apparatus and is arranged so that the position of the printing structure may be easily adjusted to facilitate the changing of the feeding discs. Various modifications in the disclosed apparatus will be obvious to those skilled in the art. For example, the apparatus may also be used with a single printing mechanism in which the lower lip portion 106 is extended beneath the location of the printing operation so that the notched disc moves the article supported on the floor lip 106 past the single offset roll. Other types of drives, adjustments and article control means may be employed. Therefore, while there has been shown and described herein a preferred embodiment of the invention it will be understood that the invention is not intended to be limited thereto or to details thereof and departures may be made therefrom within the spirit and scope of the invention as defined in the claims.

What is claimed is:

1. Apparatus for placing indicia on small articles at a high rate of speed in a printing operation comprising a disc mounted for rotation about an axis perpendicular to the plane of the disc, a plurality of outwardly opening article receiving pockets in the periphery of said disc, said pockets being generally shaped to the configuration of the article to be printed so that the surface of the articles to be printed, when disposed in said pockets, are parallel to the surface of said disc, an article retaining structure surrounding said disc adapted to provide in conjunction with said disc a hopper for holding the articles to be printed, said retaining structure having an upstanding cylindrical wall portion immediately adjacent the periphery of said disc outwardly thereof and an inwardly extending floor portion positioned below said disc adapted to provide support for articles positioned in said pockets, an aperture in said floor portion through which said articles fall from said pockets, printing apparatus disposed adjacent said aperture for applying indicia to the articles carried by said disc, and means to rotate said disc to advance articles positioned in said disc pockets past said printing apparatus to have an indicium placed thereon in a printing operation, said printed article being ejected through said aperture after the printing operation is completed.

2. The apparatus as claimed in claim 1 wherein said article retaining structure includes an inclined surface portion connecting said cylindrical wall portion and said floor portion such that the tendency of the articles when carried in said pockets by said rotating disc to move outwardly under the influence of centrifugal force is opposed by gravitational force.

3. The apparatus as claimed in claim 1 and further including control means for preventing the feeding of an article improperly positioned in a pocket comprising a fluid jet structure mounted on said upstanding cylindrical wall portion above and outwardly of the periphery of said disc and having an orifice directed inwardly across and substantially parallel to the surface of said disc, said jet structure being arranged so that fluid ejected from said orifice urges articles not properly positioned in said pockets away from the periphery of said disc.

4. The apparatus as claimed in claim 1 and further including means for inhibiting the feeding of articles by said disc comprising a fluid jet structure positioned below the path of articles carried by said disc and having an orifice directed upwardly perpendicular to the plane of rotation of said disc arranged so that fluid ejected from said orifice acts to remove articles positioned in said pockets and to prevent the feeding of articles to said printing apparatus.

5. The apparatus as claimed in claim 1 wherein said printing apparatus includes offset printing means including an engraved wheel having a plurality of depressions adapted to receive printing ink and an offset roll which

transfers ink configurations from the depressions to the articles in a printing operation, said offset printing means being driven by said disc rotating means.

6. The apparatus as claimed in claim 1 wherein said printing apparatus includes first and second printing means, each of said printing means having an ink transfer device disposed adjacent said aperture on opposite sides of said disc, said transfer devices being adapted to place ink configurations on opposite surfaces of an article carried by a disc pocket substantially simultaneously as said article is moved past said transfer devices by said disc.

7. The apparatus as claimed in claim 6 wherein each ink transfer device includes a gravure roll and an offset roll, and further including gear train means driven by said disc rotating means including a driving gear associated with each gravure roll and each offset roll and means to rotatably adjust the gravure rolls without disengaging the gravure roll driving gear from the other gears with which it meshes to enable adjustment of the relative registration of the indicia placed on said articles in the printing operation.

8. The apparatus as claimed in claim 7 and further including means to move one of said offset rolls toward and away from the other offset roll for adjusting the nip between said offset rolls to accommodate articles of different dimensions.

9. Apparatus for placing indicia on small articles in a printing operation comprising a disc mounted for rotation about an axis perpendicular to the plane of the disc, a plurality of article receiving pockets in said disc, said pockets being generally shaped to the configuration of the article to be printed so that the surface of the article to be printed, when disposed in said pocket, is parallel to the surface of said disc, an article retaining structure associated with said disc adapted to provide in conjunction with said disc a hopper to hold the articles to be printed, said retaining structure having an upstanding cylindrical wall portion immediately adjacent the periphery of said disc outwardly thereof and an inwardly extending floor portion positioned below said disc adapted to provide support for articles positioned in said pockets, an aperture in said inwardly extending floor portion through which articles carried by said pockets may fall, printing apparatus disposed adjacent said aperture and in the path of articles carried in said pockets for applying indicia to the articles carried by said disc, and means to rotate said disc to advance articles positioned in said disc pockets past said printing apparatus, said printed article being ejected through said aperture after the printing operation is completed.

10. Apparatus for placing indicia on small articles in a printing operation comprising a flat disc of resilient material, said disc being mounted for rotation about an axis perpendicular to the plane of the disc and the plane of said disc being inclined at an angle to the horizontal between 15° – 45° , a plurality of article receiving pockets in said disc, said pockets being generally shaped to the configuration of the article to be printed so that the surface of the article to be printed, when disposed in said pocket, is parallel to the surface of said disc, an article retaining structure associated with said disc adapted to provide in conjunction with said disc a hopper to hold the articles to be printed, said retaining structure having an upstanding cylindrical wall portion immediately adjacent the periphery of said disc outwardly thereof and an inwardly extending floor portion positioned below said disc adapted to provide support for articles positioned in said pockets, an aperture in said inwardly extending floor portion through which articles carried by said pockets may fall, printing apparatus disposed adjacent said aperture and in the path of articles carried in said pockets for applying indicia to the articles carried by said disc, and common drive means to rotate said disc to advance articles positioned in said disc pockets past said printing apparatus and to operate said printing apparatus for applying indicia to the articles

carried by said disc, said printed article being ejected through said aperture after the printing operation is completed.

11. The apparatus as claimed in claim 10 wherein said printing apparatus includes first and second printing means, each of said printing means having an ink transfer device disposed adjacent said aperture on opposite sides of said disc, said transfer devices being adapted to place ink configurations on opposite surfaces of an article carried by a disc pocket substantially simultaneously as said article is moved past said transfer devices by said disc.

12. The apparatus as claimed in claim 11 wherein each ink transfer device includes a gravure roll and an offset roll, and further including gear train means driven by said disc rotating means including a driving gear associated with each gravure roll and each offset roll and means to rotatably adjust the gravure rolls without disengaging the gravure roll driving gear from the other gears with which it meshes to enable adjustment of the relative registration of the indicia placed on said articles in the printing operation.

13. The apparatus as claimed in claim 12 and further including means to move one of said offset rolls toward and away from the other offset roll for adjusting the nip between said offset rolls to accommodate articles of different dimensions.

14. The apparatus as claimed in claim 10 wherein said common drive means includes a single shaft which drives a disc rotating gear train and a printing apparatus gear train and further including means to adjust the angle of inclination of said disc, said angle adjusting means adapted to be manipulated without adversely affecting the operation of said single drive shaft.

15. Apparatus for placing indicia on small articles at a high rate of speed in a printing operation comprising a 35 rotatable shaft adjustably inclinable at an angle of 15-45° to the vertical, a flat disc of resilient material removably mounted on said shaft for rotation in the plane of said disc, said disc having a plurality of outwardly opening article proceeding pockets in its periphery, said pockets 40 being generally shaped to the configuration of the articles to be printed so that the surface of the articles printed, when disposed in said pockets, are aligned generally parallel to the plane of said disc, an article retaining structure surrounding said disc adapted to provide in conjunction with said disc a hopper for holding the articles to be printed, said retaining structure having an upstanding cylindri- 45

cal wall portion positioned immediately adjacent the periphery of said disc, an inwardly extending floor portion positioned below said disc and adapted to provide support for articles positioned in said pockets, and an inclined surface portion connecting said cylindrical wall portion and said floor portion, an aperture in said floor portion through which articles carried by said pockets may fall, printing apparatus mounted adjacent said aperture comprising two rotary printing elements positioned in the paths of said pockets, one of said printing elements being disposed above the plane of said disc and the other printing element being disposed below the plane of said disc, said printing elements being spaced to permit the passage of an article carried in a disc pocket to pass between them so that ink configurations carried by said printing elements are transferred substantially simultaneously to opposite surfaces of an article carried by said disc, means for laterally adjusting the position of said printing apparatus toward and away from said rotatable shaft to facilitate the removal of said disc from said rotatable shaft and common drive means for rotating said disc to advance articles positioned in said disc pockets past said printing apparatus and for operating said printing apparatus to rotate said printing elements for applying indicia in the form of ink configurations to the articles carried by said disc.

16. Apparatus for placing indicia on small articles in a printing operation comprising a disc mounted for rotation about an axis perpendicular to the plane of the disc, a plurality of article receiving pockets in said disc, said pockets being generally shaped to the configuration of the article to be printed, an article retaining structure associated with said disc adapted to provide in conjunction with said disc a hopper to hold the articles to be printed, said retaining structure having an upstanding wall portion immediately adjacent the periphery of said disc outwardly thereof and an inwardly extending floor portion positioned below said disc adapted to provide support for articles positioned in said pockets, printing apparatus disposed in the path of articles carried in said pockets for applying indicia to the articles carried by said disc, and means to rotate said disc to advance articles positioned in said disc pockets past said printing apparatus for applying indicia to the articles in a printing operation.
